CLAIM

The ornamental design for a water polo toy, as shown and described.

DESCRIPTION

FIG. 1 is a front, right, top perspective view of a water polo toy, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a sectional view of 9-9 along the line in FIG. 3; and, FIG. 10 is a front, right, top perspective view of the water polo toy, indicating the usage environment.

The broken lines are for environmental purposes only and form no part of the claimed design.

1 Claim, 10 Drawing Sheets
